UNITED STATES PATENT OFFICE.

THOMAS J. STEARNS, OF BOSTON, MASSACHUSETTS, ASSIGNOR TO THE ROXBURY CARPET COMPANY, OF SAME PLACE.

DESIGN FOR CARPETS.

SPECIFICATION forming part of Design No. 11,612, dated January 20, 1880.

Application filed December 23, 1879. Term of patent 3½ years.

To all whom it may concern:

Be it known that I, THOMAS J. STEARNS, of Boston, in the county of Suffolk and State of Massachusetts, have invented a new and original Design for Carpets, of which the following is a specification.

The nature of my design is fully shown in the accompanying photograph.

The design consists of an angular figure, A, of a light tint, called a "light center," partly covered by darker floral designs, and an angular figure, B, of a dark tint, called a "dark center," partly covered by lighter floral designs.

I claim—

The design for a carpet, consisting of the light center A, with dark floral designs, and the dark center B, with light floral designs, as shown.

In testimony whereof I have signed my name to this specification, in the presence of two subscribing witnesses, this 16th day of December, 1879.

THOMAS J. STEARNS.
